Primary Examiner — Mark Goodwin(74) *Attorney, Agent, or Firm* — Sutherland Asbill & Brennan LLP(57) **CLAIM**

The ornamental design for a high pressure fuel injection pipe, as shown and described.

DESCRIPTION

FIG. 1 is a front view of a high pressure fuel injection pipe showing our new design;

FIG. 2 is a top view thereof;

FIG. 3 is a right side view thereof;

FIG. 4 is a left side view thereof;

FIG. 5 is an enlarged view along line 1-1 of FIG. 1;

FIG. 6 is a cross-sectional view along line 2-2 of FIG. 2;

FIG. 7 is an enlarged view along line 6-6 of FIG. 6;

FIG. 8 is an enlarged view of FIG. 4; and,

FIG. 9 is a cross-sectional view showing our high pressure fuel injection pipe in use.

The broken line showings in FIGS. 1-4, 6, 8, and 9 are for the purpose of illustrating portions of the high pressure fuel injection pipe and form no part of the claimed design. The broken line showing of a mating component in FIG. 9 is for the purpose of illustrating the usage environment of the high pressure fuel injection pipe and forms no part of the claimed design.
